Primary Examiner — Keith J Wilson(74) *Attorney, Agent, or Firm* — Cantor Colburn LLP(57) **CLAIM**

The ornamental design for a nozzle for dishwasher, as shown and described.

DESCRIPTION

FIG. 1 is a front perspective view of a nozzle for dishwasher, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof; and,

FIG. 7 is a bottom plan view thereof.

The evenly dashed broken lines illustrating portions of the nozzle for dishwasher form no part of the claimed design.

1 Claim, 7 Drawing Sheets(56)
